DOOR CHECK

Application filed February 15, 1928. Serial No. 254,361.

This invention relates to a door check, and the invention aims to provide a door check which will efficiently perform the function for which it is intended, and which will continue to so perform after long usage, and which at the same time is of a simplified construction embodying a minimum number of parts.

It is appreciated that quite a number of door checks of different kinds have heretofore been proposed. Some of these door checks have taken the form of a plunger acted upon by a spring. It has also been proposed to provide a door check in the nature of an eccentrically mounted check member adapted to engage the floor by reason of such mounting and which is held in place by a spring controlled locking member co-operating with a plurality of recesses for receiving the locking member. Here again the spring action becomes defective after a period of use. The locking device is arranged to lock the member only in a certain position and it oftentimes occurs that when the check member is in proper checking position the co-operating locking devices are out of position.

The present invention contemplates a check which takes the form of an eccentrically mounted member but, wherein all movable mechanism is eliminated except the check member itself. The invention contemplates frictional means which acts upon the rotational movement of the check member, and the entire assembly is such that this friction can be maintained throughout long usage and can be increased from time to time if the same be found necessary.

In the accompanying drawings:

Fig. 1 is a side elevational view of a door provided with a door check constructed in accordance with the invention, and indicating one position in which the check may be positioned upon a door.

Fig. 2 is a plan view of a check in non-checking position.

Fig. 3 is a view similar to Fig. 2 but showing the check moved to operative or checking position.

Fig. 4 is a sectional view taken on line 4—4

of Fig. 3, illustrating the structural features of the invention.

In Fig. 1 the door check, which is generally referenced 1, is shown applied to the lower portion and near the free edge of a door 2. This is perhaps an advantageous location for the check, although it can be placed wherever desired. The check consists primarily of two portions, one of which is a flanged member 3 which may be fixed to the door 1 by suitable screws 4 and 5. This flange member is preferably a stamping and is just deep enough to receive a nut for the attachment of the other part.

The other portion of the check consists of a plate 10 and a plate 11, both of which are preferably stampings, the plate 11 being provided with an extension 12. Between these two plates is disposed a disc of rubber 13 which is generally oval in shape, as shown in Figs. 2 and 3. Screws 14 are taken through the plate 11 and received in screw threaded apertures in the plate 10. The tightening of these screws assemble the two plates and the rubber disc together.

This second portion is rotatably mounted and for this purpose the screw or bolt 15 extends through the two plates and the rubber disc, which is made tight by a nut 16 disposed on the under side of the member 3, and preferably a lock washer 17 is used. Also it is preferable to place washers 18 and 19 on the bolt 15, as shown in Fig. 4, and these washers are such as to provide for frictional turning of the rotatable member upon the bolt 15, and for this purpose may advantageously be made of fiber. The rotatable member is eccentrically mounted on the bolt 15.

In order to mount the check on a door the proper position is first ascertained, and then the movable part may be turned by use of the extension 12, to a position which approximates that of Fig. 3, so that the screw 4 can be put into place, whereupon the check member may be reversed and the screw 5 secured in place. When the check is not in use it may be turned up as shown in Fig. 2 or in some position between that of Fig. 2 and that of Fig. 3. To check the door the rotatable part is turned upon the bolt 15 which may con-

veniently be done by actuating the extension 12 by the foot.

When the parts are in position shown in Fig. 3 the extension 12 may be depressed with some pressure. The rubber disc engages the floor at this time and there is lifting action on the door. Ordinarily, there is some slight movement in the door by reason of its hinged mounting so that the door can be raised 10 slightly. Thus, by the weight of the door itself, the door check is held down against the floor.

One of the features of the invention is the structural arrangement of the rotatable member. A disc of rubber is preferably used, as shown, and clamped between two plates. It will be seen, therefore, that if conditions ever require the clamping of the rubber disc can be increased by merely tightening the screws 20 14. The frictional resistance to the rotation of the check member is offered by the fiber washers. It will be noted that the bolt 15 extends throughout the disc of rubber and when it is tightened the disc is slightly compressed. Due to this frictional engagement 25 between the washers with the rotatable parts is maintained. However, if after long use, the friction becomes lessened it can easily be restored by tightening the screw 15.

30 It has been proposed to provide a check with a rubber ring or tire for engaging the floor. In such a construction a rubber ring is placed on its mounting under tension and the result is that the ring loses its elasticity 35 after long use thus interfering with the efficient operation of the check. By utilizing a rubber disc, however, the rubber is not under tension so that it does not become dead, even after long use. The rubber disc however, 40 may be under slight compression in order to effect the proper friction action, but this is not sufficient to materially effect the life of the rubber disc.

We claim:

45 A door check comprising a cup shaped supporting member adapted to be placed upon a door with the rim of the cup in contact therewith, securing means passing through the bottom of the cup-shaped member for holding 50 the same to the door, a check member comprising an oval disk of rubber, an inner face plate, an outer face plate, a plurality of securing devices passing through the rubber disk and holding the face plates assembled on 55 opposite sides of the disk, said face plates having their outer peripheral edges located inwardly of the outer peripheral edge of the rubber disk, one of said face plates having a projecting piece which extends beyond the 60 peripheral edge of the rubber disk and constitutes an operating handle, a bolt passing through the facing disks and rubber disk eccentric of the rubber disk and near one of its elongated sides, a nut inside the cup-shaped 65 support into which the bolt is screw threaded,

and a friction washer surrounding said bolt and located between said supporting cup and the inner face plate whereby tightening of the bolt acts upon the friction disk and to compress the rubber disk to maintain said friction, said supporting plate being positioned on the door so that when the door check element is rocked on the bolt into contact with the floor one of the short sides of the oval disk contacts with the floor.

70 In testimony whereof we affix our signatures.
